UNITED STATES PATENT OFFICE.

NORMAN MARSHALL, OF NEWTON, MASSACHUSETTS.

INCANDESCENT-LAMP SOCKET.

SPECIFICATION forming part of Letters Patent No. 783,295, dated February 21, 1905.

Application filed November 26, 1904. Serial No. 234,323.

To all whom it may concern:

Be it known that I, NORMAN MARSHALL, of Newton, in the county of Middlesex and State of Massachusetts, have invented certain new and useful Improvements in Incandescent-Lamp Sockets, of which the following is a specification.

The invention relates to adapters such as are used for adapting incandescent-lamp sockets of the type known as "T-H" sockets for use in connection with incandescent lamps of the Edison type.

Heretofore it has been customary in supplying Edison lamps to be used with T-H sockets to furnish an adapter for each lamp, which is applied to the T-H socket and is provided with terminals to coöperate with the terminals on the base of the Edison lamp. These adapters are provided with a screw-threaded central terminal for engaging the screw central terminal of the T-H socket and are held in place in the socket merely by the engagement of these screw-threaded parts. In removing an old lamp from a socket the adapter is usually removed with the lamp, and it is necessary therefore to furnish an adapter for each Edison lamp which is to be used with a T-H socket, and this has been the practice.

In practicing the present invention I provide means for preventing the removal of the adapter after it has been once applied to a T-H socket, so that in removing the lamp it is removed from the adapter, while the adapter remains as a permanent part of the T-H socket, thereby permanently transforming it into a socket adapted to receive Edison lamps. The means for preventing the removal of the adapter from the socket is so formed that it does not interfere with the application of the adapter to the socket, but prevents the rotation of the adapter in a direction to disengage the screw-threaded central terminals after the adapter has been once screwed into place.

For the purpose of illustration I have shown in the accompanying drawings a T-H socket and an adapter embodying my invention in the form in which I prefer to use it.

In the drawings, Figure 1 is an enlarged sectional view showing a T-H socket with an adapter and Edison lamp applied to the socket.

Fig. 2 is a central view through the access of the adapter, and Fig. 3 is a view of the inner end of the adapter.

As shown in the drawings, the adapter is provided with the usual metallic screw-shell 55 A for engaging the outer metallic screw-terminal B of the lamp B' and is also provided with a central internally-screw-threaded metallic terminal C for engaging the screw-terminal D of the T-H socket D'. The inner 60 end of the metallic shell A is provided with a flat annular flange A', which engages the end of the porcelain base D² of the socket when the adapter is screwed into position and forms the contact against which the switch-block of 65 the key mechanism acts in the usual manner. At the inner edge of this flange A' the shell is turned inward to form a rib A² for engaging and determining the position of the insulating disk E in which the terminal C is secured. The adapter is also provided with the usual insulating-sleeve F surrounding the metallic screw-shell A.

The means for preventing the removal of the adapter after it has been once screwed into 75 place consists of one or more spring-catches G, formed by upsetting the metal from the flange A' of the screw-shell, as indicated in Fig. 3. These spring-catches yield as they engage the end of the porcelain base D² during 80 the application of the adapter to the socket and spring outward into one or more of the recesses in the end of the porcelain as the adapter is screwed home. The catch or catches then acts against the side of the recess in the 85 porcelain to prevent rotation of the adapter in a direction to unscrew the adapter from the socket, and thus prevents the removal of the adapter and makes it a permanent part or attachment to the socket, so that the lamp B' 90 may be removed without danger of removing the adapter and a new lamp introduced. In Fig. 1 one of the catches G is shown in position in the recess of the porcelain base in which the central terminal is located, where it 95 will act against the side D³ of the recess to prevent the backward rotation of the adapter. The catches G are so arranged upon the flat flange A' that they will not interfere with the action of the switch-block upon the flange, the 100

catches being arranged within the part of the flange which registers with the switch-block of the key mechanism.

By means of the adapters embodying my invention Thomson-Houston sockets which have been once supplied with an adapter become permanently adapted for use in connection with Edison lamps, and there is no necessity thereafter for supplying adapters with lamps to be used with such sockets.

What I claim, and desire to secure by Letters Patent, is—

1. The combination with an incandescent-lamp socket provided with a central screw-terminal, and an adapter provided with a coöperating screw-terminal, and a screw-shell, of means for preventing the removal of the adapter from the socket when once applied thereto.
2. The combination with an incandescent-lamp socket provided with a central screw-terminal, and an adapter provided with a coöperating screw-terminal, and a screw-shell, of means for preventing a backward rotation of the adapter after it has been screwed into position on the central terminal.

3. An adapter provided with a central screw-terminal for engaging the central terminal of a Thomson-Houston socket, a screw-shell, and means for preventing the removal of the adapter from the socket when it has been once applied thereto.

4. An adapter provided with a central screw-threaded terminal for engaging the central terminal of a Thomson-Houston socket, a screw-shell, and one or more spring-catches for preventing backward rotation of the adapter after it has been applied to the socket.

5. An adapter provided with a central screw-threaded terminal, a screw-shell, an annular contact-flange, and one or more spring-catches on the flange.

6. An adapter provided with a central screw-threaded terminal, a screw-shell, an annular contact-flange, and one or more catches upset from the metal of the flange.

In witness whereof I have affixed my signature in presence of two witnesses.

NORMAN MARSHALL.
